UNITED STATES PATENT OFFICE.

CHARLES T. RAY, OF LOUISVILLE, KENTUCKY, ASSIGNEE TO B. F. AVERY & SONS, OF LOUISVILLE, KENTUCKY, A CORPORATION OF KENTUCKY.

MOTOR-PLOW.

1,297,908.

Specification of Letters Patent. Patented Mar. 18, 1919.

Application filed September 3, 1915. Serial No. 48,813.

To all whom it may concern:

Be it known that I, CHARLES T. RAY, a citizen of the United States, residing at Louisville, in the county of Jefferson and 5 State of Kentucky, have invented certain new and useful Improvements in Motor-Plows, of which the following is a specification.

This invention relates to motor plows and 10 consists in certain novel combinations and correlations of elements exemplified in the accompanying drawings, whereby a plow is provided having important advantages, readily understandable from the hereinafter 15 description of the particular embodiment which I prefer and accordingly, have selected to exemplify the invention: it being understood that changes in the details may be made without departing from the spirit of 20 the invention, or the scope of the subjoined claims.

In the accompanying drawings, wherein like characters of reference denote corresponding parts in the several views:

25 Figure 1 is a detail perspective view particularly intended to illustrate the relative positions of the wheels and furrow turning members in the operation of the plow.

Fig. 2 is a plan view of the implement. 30 Fig. 3 is a detail plan view of the front end of the implement, with a part of the cap broken away and a part of the casting in section, particularly intended to show gears for adjusting the guide wheel and 35 means whereby said gears may be disconnected from each other to enable said wheel freely to caster.

Fig. 4 is a vertical section on the line 4—4 of Fig. 3 with the parts in the positions they 40 occupy when arranged for the manual guidance of the implement.

Fig. 5 is a view corresponding to Fig. 4, but showing the parts in the positions they 45 occupy when the gears forming part of the means for adjusting the guide wheel are out of engagement with each other.

Fig. 6 is a side elevation of the implement.

Fig. 7 is a detail representative of the ac-

tuating lever, segment, connecting rod and 50 spring forming part of the means for adjusting the forward furrow turning member, these parts being viewed from the side opposite that shown in Fig. 6: this view also showing, by the broken lines, a position the 55 parts may assume when the furrow turning member strikes an obstruction.

Fig. 8 is a detail view of the crank 66 which forms a member of the means for adjusting the forward furrow turning member, 60 showing therein the trunnioned bearing for the connecting rod 65.

Fig. 9 is a rear end elevation of the implement.

The main frame is provided with a 65 straight side member 10 which extends from the front to the rear end of the frame. Its other members may be variously arranged to produce a frame which is wider at the rear than at the front. The frame herein 70 exemplified comprises a longitudinal member 11 arranged at the side opposite the member 10 and extending substantially parallel with the latter for a part of its length and thence extending diagonally toward the 75 front end of the member 10 as shown at 13. The rear ends of the members 10 and 11 are connected with each other by a transverse member 12. 14 designates a third longitudinal member. This is arranged between the 80 members 10 and 11 and substantially parallel with the member 10. Its rear end is suitably secured to the rear transverse member 12. These members preferably are formed of channel irons. The front ends of 85 the members 10, 13 and 14 are secured to a uniting member 15, which extends forwardly and also upwardly therefrom. This member is preferably a strong casting having horizontal flanges 15^a, upon which the 90 frame members 10, 13 and 14 respectively rest, and vertical webs 15^b against which said members respectively lie, suitable means being employed to secure the contacting parts of the members together. The uniting 95 member 15 also supports the guiding and casting means hereinafter particularly referred to, and for this purpose is provided

at the front end with a sleeve 15° surmounted by a plate 15^a.

- A designates a large traction wheel of suitable construction, which is arranged between 5 the members 10 and 14 and at or about the longitudinal center of the implement. Immediately in advance of this traction wheel there is a forward furrow turning member B of any suitable kind, the one herein shown 10 being an ordinary single moldboard plow. This forms a furrow on the bottom of which the action wheel runs. At one side of the frame there is arranged a suitable wheel C which travels upon the unplowed land and 15 is suitably mounted to be vertically adjustable in accord with the depth of the furrow in which the traction wheel runs, any of the usual or suitable means for such adjustment being employed.
- 20 At the front end of the implement there is a guide wheel D. This guide wheel is offset from the line of the forward furrow forming member and traction wheel A and traverses a furrow, made on the previous 25 travel of the implement by a rear furrow forming member E which is disposed at the rear of the traction wheel on the side of the line of the traction wheel and furrow forming member B opposite that of the guide 30 wheel.

The traction wheel is a large one and receives motion from an engine of suitable type which is geared thereto and is carried by the frame of the implement. The engine 35 is illustrated diagrammatically at F and is shown as being mounted on a bed plate 19 supported by the members 11 and 14. The engine employed is preferably of the gasoline type and in such case, a suitable radi- 40 ator, clutch etc., not necessary herein more particularly to set forth, will be provided in practice. Any suitable means for transmitting the power of the engine to the traction wheel may be employed, one such being herein exemplified. The means herein shown 45 comprises a spur gear 20 which is suitably secured to the wheel A and has its teeth engaged by a pinion 22 mounted on a trans- 50 verse shaft 23 which carries a gear 24 which meshes with a gear 25 mounted on the engine shaft 26.

The points or cutting edges of the front and back furrow forming members B and E are at the same level, and the lower surfaces 55 of the guide wheel D and traction wheel A run upon the bottom of the furrows made by said members. As already stated, the traction wheel traverses a furrow made in the same travel of the implement by the fur- 60 row forming members immediately in front of it, while the guide wheel is arranged in advance but to one side of the line of the front furrow forming member and traverses the furrow made on the previous travel of

the implement by the rear furrow forming member, as clearly shown in Fig. 1. A furrow wall is thus presented against which the guide wheel may bear and which may be used as a guide in the manual guidance of the implement. A further important advantage results from the use of furrow forming members and wheels arranged in the lines herein set forth, as forces are thereby brought into operation which overcome an objectionable extent of side draft which would tend to unnecessarily strongly press the guide wheel against the solid wall at one side of the furrow or the loose dirt at the other side of the furrow, such as occurs when furrow forming member or members arranged only at the front or only at the rear of the traction wheel, are employed. This unnecessary side draft introduces an unnecessary amount of friction for the engine to overcome.

Moreover, the employment of furrow forming members arranged as herein shown, reduces the number of travels of the implement required in plowing a field: the setting of the furrow forming member so that its point or cutting edge is level with the bottom of the traction wheel produces a furrow with a smooth even bottom by overcoming any tendency for the frame to tilt forward or back, which tendency, unless corrected, would produce an uneven furrow: and these smooth even bottoms provide most desirable bases for the traction wheel and guide wheel to traverse. When single moldboard furrow forming members, such as herein exemplified, are employed, they are set out of line with each other a distance equal to the width of the furrow which each is to make, as shown in Fig. 2, thus giving sufficient side draft to hold the inner edge of the guide wheel against the solid wall of the previously formed furrow with strength sufficient for the purpose intended to be secured, but with no undue force, that is, with no force unnecessary in proper plowing. The forward furrow forming member is arranged so that it will plow a strip one side of which is substantially in line with the outer side of the traction wheel and the other side of which is in line with the inner side of said wheel, while the rear furrow forming member is arranged to plow a strip commencing substantially in line with the inner side of the traction wheel.

The guide wheel D is connected with means whereby the implement may be guided manually, preferably from a seat 27 at the rear of the implement. This seat 27 is mounted on the upper end of a seat carrier 28, so arranged that the seat is disposed substantially in line with the straight side member 10 of the frame ad-

5 jacent to the line of which member the guide wheel D and the forward forming member B are arranged. Accordingly, the operator has an unobstructed view of said 10 guide wheel and furrow forming member and is thereby enabled to better guide the implement in a straight path. The wheel D is journaled in the lower end of a yoke 30 which is provided with a vertical pivot 31 mounted in the sleeve 15° at the front 15 end of the casting 15. The mechanism by which this wheel is turned by the operator to guide the implement preferably comprises a gear 32 which is fixed to the pivot 31 above the plate 15^a. This gear is engaged by a worm 33 mounted on a shaft 34 from which an operating rod 35 extends rearward, the rear end of the operating rod 20 having suitable means, as a hand-wheel 36, arranged convenient to the operator on the seat 27. When the rod 35 is turned by the hand wheel, motion will be communicated to the pivot 31 through the shaft 34, worm 33, and gear 32. Conversion of the 25 wheel D from a man-operated wheel to a castering wheel constitutes one of the important features of the present invention. When the particular guiding mechanism herein set forth is employed, the worm 33 and its shaft 34 are preferably carried by 30 a cap 37 which serves also to house the gear 32 and is mounted for lateral adjustment bodily on the plate 15^a, this lateral adjustment being such as to carry the worm 35 out of or into mesh with the gear 32. The cap is guided in its movements, preferably by bolts or pins 38 which extend through 40 openings 39, as shown in Fig. 3. The movements or adjustments of the cap are effected by means which may be operated from the seat 27. This means, in the herein-exemplified form of the invention, comprises an operating lever 40 which is pivoted at 41 and is provided with a rod 42 45 whose forward end is connected to an arm or crank 43 having a cam 45, the crank and cam being loosely mounted, preferably in the reduced upper end 44 of the pivot 31. The cam is arranged in an opening 46 50 formed in the cap 37. The correlation of the parts is such that the cam 45 engages the walls of the opening 46 and when turned, by the forward or rearward movement of the rod 42, operates to shift the 55 cap 37 to one side or the other according to the direction of the turning movement given the cam, it being noted that in the herein exemplified form of the invention the opening 46 is approximately rectangular and that the cam 45 engages angularly-disposed walls thereof, whereby the 60 cap is shifted with a minimum extent of movement of the rod 42 and lever 40. Suitable provision for locking the lever and

hence the cap, in adjusted position, are provided: the means herein exemplified comprising a latch, indicated at 47 in Fig. 9, the said latch being connected with a hand-piece 48 (Fig. 6) and being arranged to engage any one of the teeth 49 of a segment 50. It is only necessary that there be two teeth 49 in the segment, as there are only two positions to which the cap need be adjusted.

It will be noted that when the gears 33 and 32 are in mesh the operator has absolute control over the guidance of the implement, and as the arrangement of parts is such that the operator has an unobstructed view of the guiding wheel, he is enabled to guide the 70 implement in a straight path or to dodge an obstruction.

Short turns, at the ends of the rows, for example, may be made by releasing the guide wheel D, and locking the land wheel C, the 80 implement then turning as on a pivot around the wheel C as an axis, the power being applied to the traction wheel. It will be observed that the lower end of the yoke 30 is inclined rearward, so that the center of the 90 wheel D is out of line with the pivot 31, to facilitate the castering operation of the wheel. The locking of the land wheel C may be accomplished by any suitable braking means operable from a point within convenient reach of the operator on the seat 27. As the particular means for the purpose is not essential to the invention I do not consider it to be necessary to enter into any detailed explanation, but the mechanism herein described comprises, speaking generally, 95 a transverse shaft 51 suspended in suitable bearings provided on the frame and having a down-turned cranked end 52 near the seat. The wheel C is provided with a drum 53, and suitable brake shoes, shown at 54, are arranged to engage the drum by appropriate movement of the shaft 51, the shaft 51 being connected with the brake shoes by means which includes a rod 55 and suitable connections between the rod and the shoes.

The furrow forming members are independently adjustable relatively to the frame of the implement by mechanisms having operating members within convenient reach of 115 the operator on the seat 27 and the adjusting means are such that each furrow-forming member may be set to work at different depths and each adjusted to transport position, in a most convenient and easy way. 120 Further, the adjusting means devised by me and shown in the accompanying drawings is of such nature that the furrow-turning members may be set to work at a predetermined depth prior to the commencement of the 125 plowing operation and when in operation will be yieldably supported in order that they may ride over any obstructions and ad-

just themselves when depressions or soft spots are reached. Mechanisms having the characteristics herein set forth and which, at the same time, are of most simple and practicable construction will now be described.

Each furrow turning member B and E is provided with a vertical standard 60 which is mounted for vertical movement within a suitable guiding frame 61 carried by the frame. Each guiding frame preferably has friction-reducing rollers 62 engaging the forward and rear edges of the standard which passes through the frame. The forward furrow-turning member B is operated by a lever 63 which is pivoted at 64 to an appropriate part of the frame and is arranged adjacent to the seat 27, the lower end of the lever being connected by a rod 65 with a crank 66 projecting from a shaft 67 having a second crank 68 extending rearward therefrom (shown in dotted lines in Fig. 6), the second crank having its rear end connected to a link 69 from the upper end of which a laterally projecting pin 70 extends into any one of a plurality of apertures 71 formed in the standard 60. It will be noted that when the upper end of the lever 63 is pulled backward, the furrow-turning member B being assumed to be in working position, the connecting means between the lever and said member will be moved in a direction which raises the member to transport position. In order that the member may be adjusted to working position, when the implement is standing on unplowed land, the crank 66, as shown best in Fig. 8, has its upper end bifurcated and within this bifurcated portion there is disposed a journaled bearing 72 through which the rod 65 extends loosely. The rod projects forwardly beyond the bearing and its projecting end is encircled by a spring 73, one of whose ends preferably abuts against a stop 74 on the rod and the other of whose ends preferably abuts against the forward surface of the bifurcated portion 66^a of the crank 66. It will be seen that when the implement is standing on unplowed land and the lever 63 is thrust forward the rod 65 will be moved through the bearing 72, thereby placing the spring 73 under tension such that it exerts pressure upon the member B through the crank 66, shaft 67, crank 68, link 69 and standard 60, which pressure aids the force of gravity in the lowering of the furrow turning member to its working position when the plow enters the land. The movement of the rod 65 relatively to the crank 66, permitted by the connection described, enables the lever to be thrust forward to a position beyond that defined by the engagement of the furrow-turning member with the land and hence the furrow-turning member may be set to work at a predetermined depth while the implement is

standing upon unplowed land. A shoulder 65^a is provided on the rod to limit movement of the arm 66 under influence of the spring and prevent excessive downward movement of the member B. The lever is fixed in its predetermined position, preferably by a latch 75 (Fig. 7) arranged to engage any one of the teeth of a segment 76, the latch being preferably operated by means of a grip 77 connected with the latch by a link 78. The segment 76, instead of being fixed is pivoted, preferably on the pivot 64 of the lever 63, and a spring 79 extends from the segment to an appropriate part of the frame, to which it is secured. In practice, it is preferred to connect the forward end of the spring to a bolt 80 adjustably mounted in a projection 81 fixed upon the frame member 10, this connection permitting the tension of the spring 79 to be adjusted. It will thus be seen that when the lever is released by disengaging the latch from the segment, the lever may be moved relatively to the segment, to adjust the height of the forward furrow-turning member relatively to the frame and that when the said furrow-turning member has been adjusted to working position and the lever has been locked to the segment, the furrow-turning member is under the influence of the spring 79 and is enabled thereby to adjust itself automatically to accord with varying conditions which may be encountered in the operation, such as obstructions, depressions or soft places—the segment, the lever, and the means connecting the lever with said member, moving as a unit.

The adjusting mechanism for the rear furrow-turning member E is preferably substantially like that employed for the forward member except that the position of the rear member with relation to its actuating lever, marked 82, is such that the rod 65 is dispensed with. In other words, the segment 83 is pivoted and a spring 84 extends from the segment to an attaching means 85 carried by an appropriate part of the frame; the lever has a latch for locking it in various selected positions to the segment and its lower end is secured directly to a shaft 86, corresponding to the shaft 67, having a crank 87 with a lateral projection 88 extending into any one of several apertures provided in the standard 60 of the rear member E. This standard is vertically adjustable through an appropriate guide frame 61 having rollers 62 arranged to engage its front and rear edges. While this means connecting the rear furrow-turning member with its adjusting lever does not permit a setting of the lever beyond the point defined by the surface of the land, that is to say, while it does not employ any relatively movable connections between the lever 82 and the crank 86, it should be noted that when the rear fur-

row-turning member is set, as it is normally in ordinary plowing, in line with the bottom of the traction wheel A, the depth of the furrow made by it is always the same as that made by the front plowing element and hence there would be no particular advantage in providing means, such as are exemplified in connection with the forward furrow-turning element, for permitting a movement of the adjusting mechanism beyond that defined by the land when the implement is standing on unplowed land. In other words, the only adjustments needed for the rear plowing member are adjustments above the plane of the lower surface for working purposes.

Particular attention is called to the fact that the yieldable mountings for the furrow-turning members not only enables said members to yield to obstructions but further enables them to adjust themselves automatically when depressions or soft spots are encountered in such manner that the traction of the wheel A is not diminished. In plowing with one furrow-turning member ahead and the other behind the traction wheel, any depression or soft spot in the land would cause the weight of one side of the implement to rest on the furrow-turning members and if these members were rigidly supported the traction of the wheel A on the land would be diminished and said wheel would spin around, because of its failure to get a firm grip on the land under it. But by the use of the springs, the furrow-turning members will yield to the weight imposed on them, thus permitting the traction wheel to get a firm grip on the land under the varying conditions referred to.

It will be understood that the land wheel C is an idle wheel and that it is mounted on a crank shaft 100 having the ordinary, or any suitable means, for adjusting it to accord with the depth of plowing, this wheel running on the unplowed land while the guide wheel, the traction wheel and the plowing members run in furrows, as hereinbefore explained.

The furrow-turning members, being independently adjustable, one may be set to working position and the other in transport position, if required for any reason—when the soil is too hard for both to be used, for example.

While I prefer to employ two furrow-turning members of the single moldboard type, arranged respectively in advance and at the rear of the traction wheel, I, nevertheless, wish it to be understood that I do not limit myself in all respects to this particular number, type or arrangement of soil-turning members.

It will be noted that the frame has its member 10 arranged substantially in alignment with the longitudinal axis of the im-

plement and that the front member 13 converges forwardly toward the forward end of the member 10, and also that the uniting or connecting member 15 is substantially triangular in shape and has its rear portion extending between the members 10 and 13, its said portion being suitably secured to said members. Further, it will be noted that the member 15 extends forwardly from the front ends of the members 10 and 13 and this forward portion carries the driving wheel. Still further will it be noted that the frame has substantially a trapezoidal shape and that the longitudinal axis of the triangular connecting member 15 lies substantially in that diagonal of the trapezoid which extends from the convergent angle of the members 10 and 13 to the angle of the members 11 and 12. By this means the thrust of the guiding wheel is transmitted through the frame members in such manner as to take up the stresses incident to such thrust in a highly efficient way. It will also be observed that the quadrant 76 is provided with a stop 76' which, when the quadrant is in its normal position contacts with the bracket 64' which supports the pivot 64 of the quadrant.

Having now described the invention what I believe to be new and desire to secure by Letters Patent, is:

1. A plowing implement comprising, in combination, a single front wheel to guide the implement and support the front end of the frame, said wheel being arranged to traverse a furrow made in the previous travel of the implement, guiding connections to said wheel including elements which are relatively adjustable to release the wheel and permit the same to caster, a large traction wheel disposed rearward of the front end of the frame and set in from the line of the front wheel and at one side of the longitudinal axis of the implement, an idle land wheel arranged rearward of the front end of the frame and at the other side of the longitudinal axis of the implement, a braking means for the land wheel, and furrow forming means carried by the frame and arranged in advance of and in line with the large traction wheel, the said front wheel, traction wheel and land wheel supporting the implement and the traction wheel traversing the furrow made by the furrow forming means in the same travel of the implement.

2. A three wheel plowing implement, comprising, in combination, a supporting frame having a side member arranged substantially parallel with the longitudinal axis of the implement, an operator's seat at the rear end of said member and substantially in line therewith, a guide wheel at the front end of said member and substantially in alignment with said member and the seat, guiding connections to the wheel, having an operating

- element near the seat, a forward furrow forming member adjacent the side member and out of line with the guide wheel, the latter being arranged to traverse a furrow 5 formed in the previous travel of the implement, a large traction wheel disposed at one side of the longitudinal axis of the implement and rearward of the forward furrow forming member in position to traverse the furrow formed thereby, an idle offset land wheel at the other side of the longitudinal axis of the implement and rearward of the guiding wheel, driving mechanism carried by the frame and connected to the 10 traction wheel, and a rear furrow forming member carried by the frame and arranged rearward of the traction wheel and set in from the line of said wheel and forward furrow forming member, the said guide wheel, 15 large traction wheel and land wheel supporting the implement.
3. A three wheel plowing implement, comprising, in combination, a supporting frame having a side member arranged substantially 20 parallel with the longitudinal axis of the implement, an operator's seat at the rear end of said member, a guide wheel at the front end of said member and substantially in alignment with the seat, guiding connections 25 to the wheel, having an operating element near the seat, said guiding connections including releasable elements which are operable from the seat to permit the guide wheel to 30 caster, a forward furrow forming member adjacent the side member and out of line with the guide wheel, the latter being arranged to traverse a furrow formed by the previous travel of the implement, a large traction wheel disposed at one side of the 35 longitudinal axis of the implement and rearward of the forward furrow forming member in position to traverse the furrow formed thereby, an idle offset land wheel at the 40 other side of the longitudinal axis of the implement, the land wheel having braking means operable from the seat, driving mechanism carried by the frame and connected to the traction wheel, and a rear furrow forming member carried by the frame and arranged rearward of the traction wheel and set in from the line of said wheel and forward furrow forming member, the said 45 guide wheel, large traction wheel and land wheel supporting the implement.
4. In a three wheel plowing implement, a frame having side and end members, one outer side member being straight, the frame also including a member which unites the front end of the straight side member with the adjacent end of the front member and projects forwardly beyond said ends and has its forwardly projecting portion formed to provide a bearing which is substantially 50 in line with the straight side member, an operator's seat substantially in line with 55 said bearing, a furrow forming member at one side of the longitudinal axis of the machine and set in from the line of the guide wheel, a large traction wheel immediately rearward of said furrow forming member, 60 an idle offset land wheel on the other side of the longitudinal axis of the implement, braking means for said wheel, operable from the driver's seat, guiding connections to the guide wheel, operable from the 65 driver's seat, the guiding connections including releasable elements, and means for releasing said elements from each other to permit the guide wheel to caster, the latter means being operable from the driver's seat. 70
5. A three wheel plowing implement, comprising, in combination a frame having two substantially parallel longitudinal members arranged at one side of the longitudinal axis of the implement, a third longitudinal member at the other side of the longitudinal axis of the implement and front and back members, the front member extending diagonally from the forward end of the third longitudinal member toward the forward end 75 of the longitudinal member at the opposite side of the implement, the frame also having a uniting member which connects the forward ends of the first two longitudinal members and diagonal member with each 80 other, said uniting member projecting forwardly from said ends and having its forwardly projecting portion formed to provide a bearing arranged substantially in line with the outer one of the two first mentioned longitudinal members, a guide wheel having a spindle journaled in said bearing, a large traction wheel disposed between 85 said two first-mentioned frame members, a furrow forming member immediately in front of the traction wheel, driving mechanism for the traction wheel, mounted between the third longitudinal member and the inner one of the two first-mentioned frame members, and an idle offset land 90 wheel arranged outside the third longitudinal member. 95
6. A plowing implement, comprising, a supporting frame including a straight longitudinal member and a front end member, 100 said members having adjacent ends, the frame also including a member of substantially triangular shape which is connected to said ends and unites the same, said uniting member having a portion which projects 105 forwardly from said ends and is formed to provide a substantially vertical bearing, a guide wheel having a substantially vertical spindle journaled in said bearing, the said 110 guide wheel being arranged substantially in line with the straight longitudinal member of the frame, a furrow forming member set in from the line of the guide wheel, a traction wheel arranged rearward of said member in position to traverse the furrow 115 120 125 130

formed thereby, driving mechanism supported by the frame and connected to the traction wheel, an idle offset land wheel, an operator's seat arranged at the end of said 5 side portion of the frame opposite to the guide wheel in substantial alinement with the latter, and guiding connections to the guide wheel having an operating element adjacent to the seat.

10 7. A plowing implement, comprising a supporting frame including longitudinal members, one of which is straight and the other of which has a forward end extension which projects therefrom diagonally toward 15 the front end of the straight member, the frame also including a substantially triangular connecting member having an end located between and connected to the straight longitudinal member and diagonal 20 extension, in combination with a guide wheel journaled in the end of the substantially triangular member and disposed substantially in line with the straight longitudinal member of the frame, an operator's 25 seat at the end of the frame opposite to the guide wheel and arranged in substantial alinement with the latter, guiding connections to said wheel, having an operating element adjacent to the seat, a forward fur- 30 row-forming member set in from the line of the guide wheel, a traction wheel ar- ranged rearward of said member in position to traverse the furrow thereby, driving mechanism supported by the frame and con- 35 nected to the traction wheel, and an idle offset land wheel.

8. A plowing implement comprising, a supporting frame including a straight longitudinal member and a front end member, 40 said members having adjacent ends, the frame also including a member of substantially triangular shape which is connected to said ends and unites the same, said uniting member having a portion which projects 45 forwardly from said ends and is formed to provide a substantially vertical bearing, a guide wheel having a substantially vertical spindle journaled in said bearing, the said guide wheel being arranged substantially in 50 line with the straight longitudinal member of the frame, furrow-forming means sup- ported from the frame, an operator's seat arranged at the end of said side portion of the frame opposite to the guide wheel and 55 in substantial alinement with the latter, a traction wheel, a land wheel, and guiding connections to the guide wheel having an operating element adjacent to the seat.

9. A plowing implement comprising, a 60 supporting frame having a narrowed front end, said frame including longitudinal members, one of which is straight and the other of which has a forward end extension which projects therefrom diagonally toward the 65 front end of the straight member, the frame

also including a substantially triangular member having an end located between and connected to and uniting the front ends of the straight longitudinal member and diagonal extension and projecting forwardly 70 therefrom and provided with a vertical bearing disposed substantially in line with the straight longitudinal member of the frame, in combination with a guide wheel journaled in said bearing, a traction wheel, 75 a land wheel, and furrow forming means in advance of the traction wheel and supported from the frame.

10. In a plowing implement, a supporting frame including a straight longitudinal 80 member and a front end member, said members having adjacent ends, the frame also including a member of substantially triangular shape, which is connected to said ends and unites the same, said uniting member having 85 a portion which projects forwardly from said ends and is formed to provide a vertical bearing arranged substantially in line with the forward end of the straight longitudinal member, in combination with a front wheel 90 having a vertical spindle journaled in said bearing, said wheel supporting the front end of the frame and guiding the implement, a traction wheel located adjacent said straight longitudinal member of the frame, an offset 95 idle land wheel, and a furrow forming member carried by the frame and arranged in front of the traction wheel and inside the line of the guiding and supporting wheel.

11. In a plowing implement, a supporting frame including a straight longitudinal member and a front end member, said members having adjacent ends the frame also including a member of substantially triangular shape, which is connected to said ends 100 and unites the same, said uniting member having a portion which projects forward from said ends and is elongated substantially vertically at the front, in combination with a guiding wheel having a sub- 105 substantially vertical spindle journaled in the elongated front end of the uniting member, said guide wheel being arranged substan- tially in line with the straight longitudinal member of the frame, an operator's seat ar- ranged at the rear end of said frame member in substantial alinement with the guiding wheel, guiding connections to the 110 wheel, having an operating element near the seat, a furrow forming member carried 115 by the frame and set in from the line of the guide wheel, a traction wheel disposed rearward of the furrow forming member in position to traverse the furrow thereby, driving mechanism to said wheel carried by 120 the frame, and an idle offset land wheel con- nected to the frame.

12. In a plowing implement, a supporting frame having longitudinal members of different lengths and a front member, the 130

front member extending diagonally from the forward end of the shorter longitudinal member toward the forward end of the longer longitudinal member to form a narrow 5 rowed front end, the frame also including a member which unites the adjacent ends of the diagonal member and longer longitudinal member with each other and projects forward beyond said ends, the forwardly 10 projecting portion of the uniting member being vertically elongated and formed to provide at the front corner of the frame and substantially in line with the longer longitudinal member a bearing for the vertical 15 spindle of a guide wheel.

13. In a plowing implement, a substantially trapezoidal frame, one parallel side of the trapezoid being straight and extending parallel to the longitudinal axis of the 20 implement, one end of the frame being arranged at an acute angle to said side, and a substantially triangular uniting member having an end located between and connected to said side and end, one end of the uniting 25 member projecting from the end and side, the uniting member having its longitudinal axis lying in the diagonal of the trapezoid and provided with a bearing arranged at its front end and substantially in 30 line with the straight side of the frame, in combination with a guide wheel having a pivot journaled in said bearing, a traction wheel, a land wheel coöoperating with the guide wheel to support the frame and a furrow-forming member connected to the 35 frame.

14. In a plowing implement, the combination of a frame including a longitudinal side member provided at its front end with 40 a sleeve having its axis substantially in vertical alignment with said longitudinal member; a traction wheel, a land wheel and a guiding wheel, each supporting the frame; a furrow-forming member directly in front 45 of the traction wheel; the guide wheel being in advance of the furrow-forming member and offset therefrom to traverse a previously formed furrow and having a pivot journaled in the sleeve and being adjustable 50 independently of the other wheels in guiding the implement; and means connected to said pivot for adjusting said wheel to guide the implement.

15. A plowing implement including, in 55 combination, a supporting frame having an approximately vertically disposed sleeve at the front and a longitudinal side member arranged rearward of the sleeve and substantially in line therewith, a guide wheel 60 having a pivot journaled in the sleeve, a seat at the rear end of the side member, a land wheel, a traction wheel arranged in advance and to one side of the seat, a furrow-forming member directly in front of the

traction wheel, the guide wheel being in advance of said furrow-forming member and offset therefrom to traverse a previously formed furrow, guiding connections to the guide wheel, having an operating member near the seat and elements connecting the operating member with the pivot, said connections including gears one of which is shiftable transversely of the implement, and means for shifting the latter gear, having an operating element near the seat. 65 70 75

16. A plowing implement including, in combination, a supporting frame having an approximately vertically disposed sleeve at the front and a longitudinal side member arranged rearward of the sleeve and substantially in line therewith, a seat at the rear end of the side member, a traction wheel arranged in advance and to one side of the seat, a furrow-forming member directly in front of the traction wheel, a land 80 wheel, a guide wheel having a pivot journaled in the sleeve, said wheel being disposed in advance of the furrow-forming member in position to traverse a previously-formed furrow, guiding connections to the 85 wheel, said guiding connections including an operating element near the seat, a gear operatively connected with the pivot of the wheel and a second gear arranged to be shifted into and out of operative relation 90 with the first-mentioned gear, and means for shifting the second gear, having an operating lever near the seat and means for holding the lever in adjusted position. 95

17. In a plowing implement, a frame having a side member, a traction wheel located within the frame adjacent the side member, driving means carried by the frame and operatively connected to the traction wheel, a guide wheel journaled at the front of the 100 frame in substantial alignment with the side member, an operator's seat in substantial alignment with the side member, guiding connections to the guide wheel, having an operating element adjacent the seat, said 105 connections including members which are relatively adjustable to free the guide wheel, means operable from the seat to adjust said elements, a furrow-forming member in front of the traction wheel and set in from the 110 line of the guide wheel, and an idle offset land wheel having braking means operable 115 from the seat.

18. In a plowing implement, a frame, a traction wheel, driving means carried by 120 the frame and operatively connected to the traction wheel, a guide wheel, an operator's seat, guiding connections to the guide wheel, having an operating element adjacent the seat, said connections including members 125 which are relatively adjustable to free the guide wheel, means operable from the seat to adjust said elements, a furrow-forming

member in front of the traction wheel and set in from the line of the guide wheel, and an idle offset land wheel having braking means operable from the seat.

- 5 19. A plowing implement including, in combination a frame, a supporting and guiding wheel therefor, arranged at the front end of the frame and traversing a furrow made in the previous travel of the implement, a furrow forming member arranged after the said wheel and set in from the line thereof, a furrow wheel rearward of the furrow forming member and traversing the furrow made thereby in the same travel of 10 the implement, and a land wheel, said supporting and guiding wheel having an approximately vertical pivot and being adjustable independently of the other wheels, guiding connection to said pivot, having 15 gears one of which is adjustable into and out of operative relation with the other, and adjusting connections to the adjustable gear.
- 20 20. A plowing implement, comprising a frame, a land wheel, a traction wheel, and a furrow forming member, in combination with a single combined supporting and guiding wheel arranged at the front end of the implement and traversing a furrow made in the previous travel of the implement and 25 adjustable independently of the other wheels in guiding the implement, and having an approximately vertical pivot, and guiding connections to said pivot, including gears, a shiftable support for one of the gears, and 30 means for shifting said support transversely of the implement to adjust its gear into and out of operative relation with the other gear.
21. A plowing implement, comprising a frame, supporting wheels and a furrow-forming member, in combination with a guide wheel having an approximately vertical pivot, a gear operatively connected to the pivot, a second gear arranged to communicate motion to the first mentioned gear, a bodily shiftable carrier for the second gear, means connected to the carrier for shifting it to adjust the second gear out of or into operative relation with the first mentioned gear, and means connected to the second gear for operating it to guide the wheel when the second gear is in operative relation with the first mentioned gear.
22. A plowing implement, comprising a frame, supporting wheels and a furrow-forming member; in combination with a guide wheel having an approximately vertical pivot; a gear operatively connected to the pivot; a second gear arranged to communicate motion to the first mentioned gear; a bodily shiftable carrier for the second gear; means for shifting the carrier, including an operating lever, connections between the lever and the carrier and elements for 50 holding the lever in adjusted position; and means connected to the second gear for operating it to guide the wheel when the second gear is in operative relation with the first mentioned gear.
23. A plowing implement, comprising a frame, supporting wheels and a furrow-forming member; in combination with a guide wheel having an approximately vertical pivot; a gear operatively connected to the pivot; a worm arranged to communicate motion to the first-mentioned gear; a carrier for the worm shiftable bodily transversely of the implement, means for shifting the carrier, including an operating lever, connections between the lever and the carrier and elements for holding the lever in adjusted position; means for guiding the carrier while it is being shifted bodily, and means for operating the worm to guide the wheel when the worm is in operative relation with the first mentioned gear.
24. A plowing implement, comprising a frame, supporting wheels and a furrow-forming member, in combination with a guide wheel having an approximately vertical pivot, a gear operatively connected to the pivot, a second gear arranged to communicate motion to the first-mentioned gear, a laterally shiftable carrier for the second gear, having an opening, a cam arranged in the opening and engaging the walls thereof, means for operating the cam to adjust the carrier to move the second gear into or out of operative relation with the first mentioned gear, and means connected to the second gear for operating it to guide the wheel when the second gear is in operative relation with the first gear.
25. A plowing implement, comprising a frame, supporting wheels and a furrow-forming member, in combination with a guide wheel having an approximately vertical pivot, a gear operatively connected to the pivot, a second gear arranged to communicate motion to the first mentioned gear, a laterally shiftable carrier for the second gear, having an angular opening, a cam arranged in the opening and engaging angularly disposed walls thereof, means for operating the cam to adjust the carrier to move the second gear into or out of operative relation with the first mentioned gear, and means connected to the second gear for operating it to guide the wheel when the second gear is in operative relation with the first gear.
26. A plowing implement, comprising a frame, supporting wheels and a furrow-forming member, in combination with a guide wheel having an approximately vertical pivot, a gear operatively connected to the pivot, a cap mounted over the gear and housing the same and shiftable relatively.

thereto, a second gear carried by the cap and movable thereby into or out of operative relation with the first mentioned gear, and means connected to the second gear for operating it to guide the wheel when the second gear is in operative relation with the first mentioned gear.

27. In a plowing implement, a frame, a guide wheel having an approximately vertical pivot, a gear operatively connected to the pivot, a cap housing the said gear and shiftable bodily on the frame relatively thereto, means for shifting the cap, means for guiding the cap while it is being shifted, 10 a second gear carried by the cap and movable thereby into and out of operative relation with the first mentioned gear, and means connected to the second gear for operating it to guide the wheel when the second gear is 15 in operative relation with the first mentioned gear.

28. In a plowing implement, a frame, a guide wheel having an approximately vertical pivot, a gear operatively connected to the pivot, a cap housing the said gear and shiftable bodily on the frame relatively thereto, means for shifting the cap, including an operating lever and means for fixing the lever in adjusted positions, means for guiding 25 the cap while it is being shifted, a second gear carried by the cap and movable thereby into and out of operative relation with the first mentioned gear, and means connected to the second gear for operating it to 30 guide the wheel when the second gear is in operative relation with the first mentioned gear.

29. A plowing implement, comprising a frame, supporting wheels and a furrow-forming member, in combination with a guide wheel having an approximately vertical pivot, a gear operatively connected to the pivot, a cap mounted over the gear and housing the same and shiftable relatively thereto, said cap having an angular opening, a cam mounted in said opening and engaging angularly disposed walls thereof, means for operating said cam to shift the cap laterally, said means including a crank having connection with the cam and an operating lever having connection with the crank and provided with means for holding it in adjusted position, a gear carried by the cap and moved thereby into and out of operative relation with the first mentioned gear, and means connected to the second mentioned gear for operating it to guide the wheel when it is in operative relation with the first mentioned gear.

30. A plowing implement, comprising a frame and frame-supporting wheels, one of said supporting wheels being arranged at the front end of the frame and traversing a furrow made in the previous travel of the im-

plement, and mounted to constitute an independently movable convertible guiding and castering wheel, connections to said wheel including gears operable to guide the wheel positively when in mesh with each other and means for adjusting one of said gears transversely of the implement out of mesh with the other to free the wheel to follow the furrow.

31. A plowing implement, comprising a frame and frame-supporting wheels, one of said supporting wheels being arranged to travel in a furrow and mounted to constitute an independently movable convertible guiding and castering wheel, said wheel having an approximately vertical pivot provided with a gear, a cap housing the gear and shiftable bodily on the frame relatively to the gear, and a second gear carried by the cap and movable thereby out of mesh with the first mentioned gear to free the wheel to follow the furrow.

32. A plowing implement, comprising a frame and frame-supporting wheels, one of said supporting wheels being arranged to travel in a furrow and mounted to constitute an independently movable convertible guiding and castering wheel, said wheel having an approximately vertical pivot provided with a gear, a cap housing the gear and shiftable bodily on the frame relatively to the gear, a second gear carried by the cap, means for shifting the cap to thereby move the second gear into and out of mesh with the first gear, to free the wheel to follow the furrow and to enable said wheel to be guided by the operator, respectively, means for holding the cap in adjusted position, means for guiding it while it is being shifted, and means connected to the second gear for adjusting the same to guide the wheel when said gear is in mesh with the first mentioned gear.

33. A plowing implement, comprising a frame and frame-supporting wheels, one of said supporting wheels being arranged at the front end of the frame and traversing a furrow made in the previous level of the implement, and being mounted to constitute an independently movable convertible guiding and castering wheel, said wheel having an approximately vertical pivot provided with a gear, a cap housing the gear and shiftable bodily on the frame relatively to the gear, a second gear carried by the cap and movable thereby into and out of mesh with the first-mentioned gear, connections to said cap for shifting the same, means for holding the connections in adjusted position, means for guiding the cap while it is being shifted, and connections to the second gear for guiding the wheels when the gears are in mesh with each other.

34. A plowing implement comprising a

frame and frame supporting wheels, one of said supporting wheels being arranged at the front end of the frame and traversing a furrow made in the previous travel of the implement, and being mounted to constitute a convertible guiding and castering wheel, connections to said wheel including gears operable to guide the wheel positively when in mesh with each other, a carrier for one 10 of said gears, shiftable bodily on said frame, means for shifting said carrier to thereby move its gear into or out of mesh with the other, elements for holding the shifting means in adjusted position, and means for 15 guiding the gear carrier while it is being shifted.

35. A plowing implement comprising a frame, and a traction wheel and an idle land wheel partly supporting the frame: in combination with an additional supporting wheel arranged to traverse a furrow and operable to guide the implement; guiding connections to the last named wheel, including relatively adjustable elements through 20 which the wheel is guided positively when they are engaged with each other, the wheel being free to caster when said elements are not engaged with each other and being movable independently of the other wheels in 25 guiding the implement; a braking means for the land wheel; and means by which one of the relatively adjustable elements of the guiding connection is adjusted into and out of operative relation with the other.

36. A plowing implement, comprising a frame; a traction wheel and an idle land wheel partly supporting the frame; a furrow forming member in front of the traction wheel; and an operator's seat: in combination with an additional supporting wheel, arranged to traverse a furrow made in the previous travel of the implement; guiding connections to the last named wheel, including elements through which the wheel is 30 guided positively from the driver's seat, said elements being relatively adjustable from the seat to free the wheel and permit it to caster and said wheel being movable independently of the other wheels in guiding the 35 implement; a braking means, for the idle land wheel, operable from the driver's seat; and power means connected to the traction wheel.

37. A plowing implement, comprising a frame; a traction wheel and an idle land wheel partly supporting the frame; and a furrow forming member in front of the traction wheel: in combination with a combined supporting and guiding wheel arranged at 40 the front end of the implement and outside the line of the furrow forming member and traction wheel to traverse a furrow made in the previous travel of the implement; guiding connections to the last named wheel in-

cluding elements operable to guide the wheel 65 positively, said elements being relatively adjustable to free the wheel and permit it to caster and said wheel being movable independently of the other wheels in guiding the implement; a braking means for the idle 70 land wheel; and power means connected to the traction wheel.

38. A three wheeled plowing implement, comprising a frame, having a longitudinal side member and provided with a substantially vertical bearing at the front end of said member and in line therewith, a fork having downwardly and rearwardly extending arms and provided above the arms with a pivot mounted in said bearing, a convertible 75 castering and guide wheel journaled between the arms of the fork and arranged substantially in line with the front end of the side member of the frame, a traction wheel, driving means connected to the traction wheel, a furrow forming member in advance of the traction wheel and set in from the line of the guide wheel, the latter being arranged to traverse a previously formed furrow, an idle offset land wheel, 80 braking means for the land wheel, and means for releasing the guide wheel to permit it to caster.

39. In a motor plow, the combination of a frame, a traction wheel, means for driving the traction wheel and furrow forming members respectively arranged forward and rearward of the traction wheel and yieldable upwardly to an obstruction and to cause the 95 tractive effect of the wheel upon the land 100 to be maintained if a soft spot or depression is encountered.

40. In a motor plow, the combination of a frame, a traction wheel at one side of the frame, an idle offset land wheel, at the other side of the frame, means for driving the traction wheel and furrow forming members arranged on the same side of the implement as the traction wheel and respectively forward and rearward of the axis of the latter, 105 and springs connected to said members for holding the same in action and permitting them to yield vertically when downward weight is imposed thereon, whereby the tractive effect of the wheel upon the land is 110 maintained if a soft spot or depression is encountered, the springs also enabling the furrow forming members to yield to obstructions.

41. In a motor plow the combination with 120 a frame, a supporting and guiding wheel arranged at the front end of the frame to run in a furrow formed in the previous travel of the implement, a large traction wheel set in from the line of the guiding 125 wheel and arranged rearward of the axis thereof and at one side of the frame, means carried by the frame for driving the traction

wheel, and an idle land wheel for supporting the other side of the frame, of a mold-board plow immediately in advance of the traction wheel and forming the furrow 5 therefor, a second moldboard plow set in from the line of the first plow arranged rearward of the axis of the traction wheel and forming the furrow for the guiding wheel, and upwardly yielding connections between 10 the plows and the frame whereby the trac-

tional effect of the traction wheel upon the land is maintained and obstructions are passed.

In testimony whereof I affix my signature in the presence of two witnesses.

CHARLES T. RAY.
